UNITED STATES PATENT OFFICE

WILLIAM S. STAPLEY, OF BRIDGEPORT, CONNECTICUT, ASSIGNOR TO BRIDGEPORT BRASS COMPANY, OF BRIDGEPORT, CONNECTICUT, A CORPORATION OF CONNECTICUT.

SOCKET-CAP.

No. 884,624.

Specification of Letters Patent.

Patented April 14, 1908.

Application filed October 22, 1907. Serial No. 398,608.

To all whom it may concern:

Be it known that I, WILLIAM S. STAPLEY, a citizen of the United States, residing at Bridgeport, county of Fairfield, State of Connecticut, have invented a new and useful 5 Socket-Cap, of which the following is a specification.

This invention relates to the manufacture of electric socket shells and has for its object to provide socket caps which shall be 10 neat and attractive in appearance, perfectly rigid in use and so constructed as to reduce the cost of production to the minimum.

With these and other objects in view I 15 have devised the novel socket cap of which the following description in connection with the accompanying drawing is a specification, reference characters being used to indicate the several parts.

20 Figure 1 is a vertical section of the completed socket cap; Fig. 2 an inverted plan view thereof; Fig. 3 a section of the body as formed; Fig. 4 an inverted plan view of the body; and Fig. 5 is a section of the hub before attachment to the body.

25 My novel socket cap comprises two parts only, a sheet metal body indicated by 10 and a hub or bushing indicated by 11 which may be formed in any suitable manner as from a 30 rod. The special configuration of the body is of course wholly unimportant so far as the principle of the invention is concerned. As shown, it may be described as broadly dome-shaped. It is provided at the top, or apex of 35 the dome, with a central opening indicated by 12, the metal surrounding the opening being turned inward to form a flange 13. The opening and the flange are in practice made polygonal in form. In the present instance I 40 have shown a twelve-sided opening and flange, that is an opening and flange formed by means of a dodecahedral punch. At the lower end of the hub is a flange 14 which just passes within the flange on the body and the 45 lower end of which is beveled as at 15. The hub is also shown as provided with an internal screw thread indicated by 16, although this screw thread is incidental so far as the present invention is concerned. In assem- 50 bling, flange 14 on the hub is passed within flange 13 on the body, the top of the body resting against the shoulder 17 at the base of the flange on the hub, and then the flange on the hub is subjected to the action of a polyg- 55 onal alternately grooved and ribbed spread- ing and closing punch which curls the flange

on the hub over outward and with it the flange on the body and closes the two flanges down upon the inner side of the top of the body. I thus clamp the edge of the body 60 surrounding opening 12 between the closed down flanges and the shoulder, flange 13 on the body being folded against the under side of the body and forming an additional thickness of the metal of the body at the joint, 65 thus providing a maximum amount of strength at just the point where strength is required. In practice, the ribs on the punch (not shown) correspond with the planes of the polygonal opening and flange on the 70 body. Coincidentally with the outward curling of the flange on the hub, the metal of said flange is forced into engagement with the planes of the polygonal opening and flange on the body, thereby locking the hub 75 to the body in such a manner as to prevent the possibility of rotation of the body on the hub when the cap is screwed tight upon a nipple.

Having thus described my invention I 80 claim:

1. A socket cap comprising a body having a central opening and surrounding said opening an inwardly turned flange and a hub having a flange adapted to pass within the flange 85 on the body and a shoulder against which the top of the body rests, the parts being locked together by spreading the flange on the hub and clamping the edge of the body surrounding the opening and also the flange 90 on the body between the flange on the hub and the shoulder.

2. A socket cap comprising a body having a central polygonal opening and surrounding said opening an inwardly turned polygonal 95 flange and a hub having a flange adapted to pass within the flange on the body and beveled at its lower end and a shoulder against which the top of the body rests, the parts being locked against rotation by spreading the 100 flange on the hub and clamping the edge of the body surrounding the opening and also the flange on the body between the flange on the hub and the shoulder and forming grooves in the upset hub flange correspond- 105 ing with the planes of the flange on the body.

In testimony whereof I affix my signature, in presence of two witnesses.

WILLIAM S. STAPLEY.
